UNITED STATES PATENT OFFICE

101,237

DESIGN FOR A PARKING METER

Samuel Lee Miller, Maywood, Ill., assignor to
Miller Meters Inc., Chicago, Ill., a corporation
of Illinois

Application July 30, 1936, Serial No. 64,132

Term of patent 7 years

To all whom it may concern:

Be it known that I, Samuel Lee Miller, a citizen of the United States, residing at Maywood, in the county of Cook and State of Illinois, have invented a new, original, and ornamental Design for a Parking Meter, of which the following is a specification, reference being had to the accompanying drawing forming a part thereof.

Figure 1 is a front elevation of the parking meter showing my new design;

Fig. 2 is a rear elevation; and

Fig. 3 is a side elevation of the same.

I claim:

The ornamental design for a parking meter, as shown.

SAMUEL LEE MILLER.
